UNITED STATES PATENT OFFICE

ARTHUR ROBERTS AND JACK SHELTON, OF EAST ST. LOUIS, ILLINOIS

SIGN

Application filed November 9, 1931. Serial No. 573,994.

This invention appertains to new and useful improvements in signs and more particularly to a sign of the changeable exhibitor type.

The principal object of this invention is to provide a sign particularly adapted for use at gasoline stations for indicating the price of gasoline which frequently fluctuates to the end that the cost of indicating the prevailing prices of gasoline be reduced.

Another important object of the invention is to provide a changeable exhibitor, capable of being operated in an easy and convenient manner, and wherein provisions are maintained for ready repair and replacement of parts.

These and other important objects and advantages of the invention will become apparent to the reader of the following specification.

In the drawings:—

Figure 1 represents a front elevational view of the sign.

Fig. 2 represents a side elevational view of the sign.

Fig. 3 represents a bottom plan view of the sign.

Fig. 4 represents a sectional view taken substantially on line 4—4 of Fig. 2.

Fig. 5 represents a vertical sectional view taken substantially on line 5—5 of Fig. 4.

Fig. 6 represents a horizontal sectional view taken substantially on line 6—6 of Fig. 4.

Fig. 7 represents a fragmentary detailed sectional view through one closure plate of the device.

Referring to the drawings wherein like numerals designate like parts, it can be seen in Fig. 1, that numeral 5 represents a suitable post or support having a horizontal arm 6 thereon. From this arm can be suspended the novel sign generally referred to by numeral 7, through the agency of suitable hangars 8.

In carrying out the present invention, it can be seen that numeral 9 represents a rectangular-shaped frame having the front closure plate 10 and the rear closure plate 11. Each of the plates 10 and 11 is secured to the frame

9 by suitable securing elements 12, and each has a relatively large opening 13 and a somewhat smaller opening 14, each being surrounded by a rim 15 for supporting a pane 16 of glass or similar material. The bottom 55 of the frame 9 has an opening 17 therein over which the closure plate 18 is disposed and removable to permit access to the interior of the casing defined by the frame 9 and plates 10 and 11.

Inside of the aforementioned casing, and adjacent each of the plates 10 and 11 is a pair of upper rollers 19 and 20, and a corresponding lower pair of rollers 21 and 22. Trained over the upper and lower rollers 20 65 and 22 at the front and rear of the casing are the webs 23, while trained over the upper and lower rollers 19 and 21 at the front and rear of the casing are the webs 24.

As is clearly shown in Fig. 6, the inner ends 70 of the rollers 19 and 20 or 21 and 22 are provided with reduced portions 25 engaging into a bearing 26, there being a pair on the bottom of the frame 9 and a pair on the top of the frame 9.

The outer ends of the rollers 19 to 22 inclusive are each provided with a crank handle 27 operating through a side of the frame 9, whereby the corresponding roller can be rotated to feed the corresponding web 23 or 24 80 in the desired direction.

At this point, it can be observed that the larger web 24 is provided with suitable characters 28 thereon such as a basic cents price for gasoline or some other commodity, while characters 29 are provided on the smaller web 23 for indicating fractions of a cent and other information, which must from time to time be changed to conform with marked 85 prices.

Extending horizontally between the side portions of the frame 9 is the bar 30 which supports the lamp sockets 31, each having a lamp 32 engaged therewith. Depending 95 downwardly from the bar 30 at each side of the bulbs 32 are the sheets 33 of mesh material, their primary purpose being to maintain the webs 23 and 24 spaced from the bulbs 32 at all times, so that there is no change 100

whatsoever that the bulbs can ignite the webs.

While the foregoing specification sets forth the invention in specific terms, it is to be understood that numerous changes in the shape, size and materials may be resorted to without departing from the spirit and scope of the invention as claimed hereinafter.

Having thus described our invention, what we claim as new is:—

- 10 1. An exhibitor of the character described comprising a casing open at a pair of its opposite sides, a vertically travelling exhibitor web disposed over each open side, a horizontal member mounted in the casing, bulbs mounted on the horizontal member and a fine mesh screen disposed over the said member so as to depend at opposite sides thereof to diffuse the light emanating from the bulb in the direction of the webs.
- 15 2. An exhibitor of the character described comprising a casing open at a pair of its opposite sides, a travelling web for disposition over each open side of the casing, a horizontal member mounted in the casing and between the webs, an electric lamp depending from the member, and a pair of fine mesh aprons depending from the member, one at each side of the lamp to diffuse light emanating from the lamp in the direction of the webs.

In testimony whereof we affix our signatures.

ARTHUR ROBERTS.
JACK SHELTON.
